TAXI HAILING FLAG

Theodore Swertlow, Bronx, N. Y.

Application June 22, 1945, Serial No. 600,853

5 Claims. (Cl. 287—58)

1

This invention relates to new and useful improvements in a taxi hailing mechanism and has more particular reference to a hailing flag.

More specifically the invention proposes the construction of an extendable and collapsible member adapted to be carried in one's pocket or pocketbook when collapsed and when opened up being capable of attracting attention of a passing taxicab. It is proposed to attach a flag to the outer end of said member, which may then be waved to hail the taxi. It is advisable that the flag be waterproof, and that it be imprinted with luminous material so that it is better visible at night so as to reduce the inconvenience afforded the public when hailing taxicabs in dark or congested areas.

The invention proposes variations and embodiments, one of which has been disclosed in this specification. Particularly it is proposed that the extendable and collapsed member be of varied design. In one form of the invention it is in the nature of a plurality of telescopically engaged tubular sections. In another form of the invention it is a combination of telescopically engaged tubular sections and a lazy-tong construction.

The invention also proposes a novel and improved means for holding the collapsible member in its extended position.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:

Fig. 1 is a perspective view of a taxi hailing flag constructed in accordance with one form of this invention and illustrated in a collapsed position.

Fig. 2 is a perspective view of the hailing flag shown in Fig. 1 in its extended position.

Fig. 3 is an enlarged vertical sectional view of Fig. 2.

Fig. 4 is a fragmentary enlarged vertical sectional view taken on the line 4—4 of Fig. 3.

Fig. 5 is a fragmentary enlarged vertical sectional view taken on the line 5—5 of Fig. 3.

Fig. 6 is a fragmentary horizontal sectional view taken on the line 6—6 of Fig. 3.

Fig. 7 is a side elevational view of a taxi hailing flag, constructed in accordance with a modified form of this invention.

The new and improved taxi hailing flag, in ac-

cordance with that form of the invention illustrated in Figs. 1 to 6 inclusive, includes an extendable member 10 adapted to be carried around in one's pocket, or pocketbook when collapsed and having an inner end 11 by which it may be waved when opened. A flag 12 is attached upon the outer end of the member 10. It is proposed to so construct the collapsible member 10 that when it is in its collapsed position it is no larger than a pencil, or fountain pen so that it may be conveniently handled the same way as a pencil, or pen. Preferably, the flag 11 is provided with luminous sections 14 so that it may easily be seen in the dark; and it is preferably detachably attached to the device for purposes of replacing, washing, etc.

The extendable and collapsible member 10 includes a pair of telescopically engaged non-rotative tubular sections 15 and 16 adapted to be extended and collapsed relatively to each other. The inner end of the inner section 15 is provided with an outwardly directed flange 18 and the adjacent end of the outer section 16 is provided with an inwardly directed flange 19 which extends over said outwardly directed flange 18 and which continues into an inwardly directed short tubular portion 20 spaced outwards from the inner section 15 so as to form a small space, or chamber 21.

A pin 22 is mounted on and projects from the inwardly directed short tubular portion 20 and engages into a longitudinally extending slot 23 for holding the sections 15 and 16 against rotation. As illustrated in Figs. 3, 4 and 5, the sections 15 and 16 are fully extended. A spring urged pin 25 engages through an aperture 26 in said inwardly directed short tubular portion 20 and extends across the space or chamber 21 and engages into another aperture 27 formed in the inner section 15 for holding the sections 15 and 16 in their extended positions.

A cam-like leaf spring 28 is mounted within the inner section 15 by several fastening elements 29. This cam-like leaf spring 28 is provided with a cam portion 30 which engages against the inner end of the pin 25 for urging the pin 25 outwards when the cam portion 30 is moved outwards for releasing the sections 15 and 16. The pin 25 is urged and held in its inner position by a spring 32 which is supported beneath the flange 19 and on section 16 and which is attached to the head of the pin 25. The spring 28 normally seeks an inward positions, as illustrated in Fig. 4.

The member 10 is provided with another tele-

scopic section 34 slidably engaging the inner section 15 and when moved inwards capable of engaging against the cam-like leaf spring 28 for moving the leaf spring 28 outwards so that the cam portion 30 moves the pin 25 outwards free from the aperture 27. The section 34 extends above the section 15. Said section 34 looks very similar to a piston and stem. It has a piston portion 35 slidably engaged within the section 15 and which connects with a thin stem portion 36. The top of the stem portion 36 is provided with a head 31. The hailing flag 12 is attached to the stem portion 36. The flag 12 is capable of being wound around the stem portion 36 so that it may be lowered down into the section 15 when the member 10 is collapsed. A stop 38 is attached upon the flange 18 radially inwards and when the section 34 is pushed into the section 15 the bottom face of the piston portion 35 engages the stop 38 to limit the downward movement of the piston portion 35 and the stem portion 36 and the flag 12 carried thereby.

The inner end of the extendable and collapsible member 10 is also a tubular section in which the tubular section 16 is slidably engaged. The adjacent end portions of the sections 11 and 16 are constructed identically in the same way as the adjacent end portions of the sections 15 and 16. Identical parts have been indicated by the same reference numerals. However, the flange 18 of the section 15 is depended upon to press outwards the leaf spring 28 of the section 16 for releasing the sections 11 and 16. Stops 42 are mounted upon the bottom flange 18 of the section 16 for limiting the possible downward motion of the section 15 within the section 16. The stops 42 also extend outwards and engage in longitudinally extending grooves 46 formed along the sides of the section 11 for holding the sections 11 and 16 non-rotative in relation to each other. The bottom of the section 11 is provided with a removable cap 47.

The side of the section 11 is also provided with a clasp 40 or hook for securing the hailing flag in a man's pocket, canopy of a building, etc.

The operation of the new and improved taxi hailing flag may be understood from the following:

When the flag is open as illustrated in Fig. 2 it may be used to hail taxicabs, or for other hailing or signaling purposes. The hailing flag may be collapsed by first turning the flag 12 around the stem portion 36 of the section 34. Now the section 34 may be moved downwards into the section 15. When the section 34 is in its complete downward position, the piston portion 35 will have moved the cam-like leaf spring 28 of the section 15 outwards which moved the pin 25 outwards freeing the sections 15 and 16. Now the section 15 is free to be moved downwards into the section 16.

When the section 15 reaches its bottommost position within the section 16 it will have moved the spring 28 of the section 16 which will have freed the sections 11 and 16. Now the section 16 may be moved downwards to its bottom position within the section 11 and the hailing flag will be collapsed and appears as illustrated in Fig. 1.

In Fig. 7 a modified form of the invention has been disclosed in which the hailing flag includes an extendable and collapsible member 50 adapted to be carried around in one's pocket, or pocket-book when collapsed and having an inner end 51 by which it may be waved when opened. A

flag 12 is attached upon the outer end of the member 50.

The member 50 is constructed from a plurality of pivotally connected strip sections 52 arranged in the nature of a lazy-tong member. The inner end 51 is in the nature of a tubular container 53 which is connected with the inner end of the lazy-tong member 50. One of the inner strips of the lazy-tong member is pivotally connected by a pintle 54 within the container 53. The other inner strip is pivotally connected with a slide 55 slidably mounted on a bar 56 within the container 53. The outer end of the lazy-tong member 50 has one of the ends of one of the end strips pivotally connected by a pintle 57 with a bar 58 upon which the flag 12 is attached. The outer end of the other end strip of the lazy-tong member 50 is connected by a pintle 59 with a slot 60 formed in the bar 58. The arrangement is such that the lazy-tong member may be extended and collapsed. It is illustrated in Fig. 7 in its extended position. When collapsed the flag 12 may also be forced into the container 53 and then the hailing flag may be conveniently carried around in one's pocket.

An outer cap 61 is provided for encasing this device in the fully collapsed condition.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a taxi hailing flag, an adjacent pair of telescopically engaged non-rotative tubular sections adapted to be extended and collapsed and the inner end of the inner section having an outwardly directed flange and the adjacent end of the outer section having an inwardly directed flange extending over said outwardly directed flange and continuing into an inwardly directed flange and continuing into an inwardly directed short tubular portion spaced outwards from said inner section, said inner section including an aperture, a spring urged pin engaging through said short tubular portion and extending across the space to said inner section and engaging in said aperture of said inner section for holding said sections extended, a cam-like leaf spring mounted within the inner section and engaging the inner end of said pin for moving said pin outwards when moved outwards for releasing said sections, and another telescopic section slidably engaging in said inner section and when moved inwards acting to move said leaf spring outwards.

2. In a taxi hailing flag, an adjacent pair of telescopically engaged non-rotative tubular sections adapted to be extended and collapsed and the inner end of the inner section having an outwardly directed flange and the adjacent end of the outer section having an inwardly directed flange extending over said outwardly directed flange and continuing into an inwardly directed short tubular portion spaced outwards from said inner section, said inner section including an aperture, a spring urged pin engaging through said short tubular portion and extending across the space to said inner section and engaging in said aperture of said inner section for holding said sections extended, a cam-like leaf spring mounted within the inner section and engaging the inner end of said pin for moving said pin

outwards when moved outwards for releasing said sections, another telescopic section slidably engaging in said inner section and when moved inwards acting to move said leaf spring outwards, and a stop mounted on said inner section and projected radially inwards to be engaged by the bottom end of said other telescopic section when moved completely into said inner section to limit inward movement of said other telescopic section.

3. In a taxi hailing flag, an adjacent pair of telescopically engaged non-rotative tubular sections adapted to be extended and collapsed and the inner end of the inner section having an outwardly directed flange and the adjacent end of the outer section having an inwardly directed flange extending over said outwardly directed flange and continuing into an inwardly directed short tubular portion spaced outwards from said inner section, said inner section including an aperture, a spring urged pin engaging through said short tubular portion and extending across the space to said inner section and engaging in said aperture of said inner section for holding said sections extended, a cam-like leaf spring mounted within the inner section and engaging the inner end of said pin for moving said pin outwards when moved outwards for releasing said sections, another telescopic section slidably engaging in said inner section and when moved inwards acting to move said leaf spring outwards, and a stop mounted on said inner section and projected radially inwards to be engaged by the bottom end of said other telescopic section when moved completely into said inner section to limit inward movement of said other telescopic section.

4. In a taxi hailing flag, an adjacent pair of telescopically engaged non-rotative tubular sections adapted to be extended and collapsed and the inner end of the inner section having an outwardly directed flange and the adjacent end of the outer section having an inwardly directed flange extending over said outwardly directed flange and continuing into an inwardly directed short tubular portion spaced outwards from said inner section, said inner section including an aperture, a spring urged pin engaging through said short tubular portion and extending across the space to said inner section and engaging in said aperture of said inner section for holding

said sections extended, a cam-like leaf spring mounted within the inner section and engaging the inner end of said pin for moving said pin outwards when moved outwards for releasing said sections, and another telescopic section slidably engaging in said inner section and when moved inwards acting to move said leaf spring outwards, said spring which urges said pin inwards being mounted beneath said inwardly directed flange and being connected with a head on said pin.

5. In a taxi hailing flag, an adjacent pair of telescopically engaged non-rotative tubular sections adapted to be extended and collapsed and the inner end of the inner section having an outwardly directed flange and the adjacent end of the outer section having an inwardly directed flange extending over said outwardly directed flange and continuing into an inwardly directed short tubular portion spaced outwards from said inner section, said inner section including an aperture, a spring urged pin engaging through said short tubular portion and extending across the space to said inner section and engaging in said aperture of said inner section for holding said sections extended, a cam-like leaf spring mounted within the inner section and engaging the inner end of said pin for moving said pin outwards when moved outwards for releasing said sections, and another telescopic section slidably engaging in said inner section and when moved inwards acting to move said leaf spring outwards, and fastening elements securing the top end of said cam like leaf spring to said inner section.
